UNITED STATES PATENT OFFICE.

TORSTEN ALFONSO GYLDSORFF, OF DETROIT, MICHIGAN.

HAIR-PIN.

1,226,508.

Specification of Letters Patent. Patented May 15, 1917.

Application filed January 18, 1916. Serial No. 72,840.

To all whom it may concern:

Be it known that I, TORSTEN A. GYLDSORFF, a subject of the King of Sweden, residing at Detroit, in the county of Wayne and State of Michigan, have invented new and useful Improvements in Hair-pins, of which the following is a specification.

This invention relates to hair pins and has for its primary object the provision of a device of this character so constructed that the same will be effectively held within the hair and having the inherent property of gripping a relatively large amount of hair and holding the hairs gripped against independent movement.

An object of the invention is to provide a two part hair pin in which the parts are so constructed and arranged that they will be positively held against bodily movement away from each other when being applied to the hair.

Another object of the invention is to so construct the device that the point of attachment between the parts will not interfere with the resiliency of the parallel limbs or those portions between which the hair lodges.

With these and other objects in view the invention consists in the construction, combination and arrangement of parts as will be hereinafter more fully described, illustrated in the accompanying drawing and pointed out in the claims hereunto appended.

Similar reference characters indicate corresponding parts throughout the several views.

In the drawing:

Figure 1 is a front elevation of the hair pin, and

Fig. 2 is a top plan view thereof.

In the drawing the numeral 1 designates a central member of a well known construction with the exception that the limbs 2 of the member are oppositely bowed intermediate their ends as indicated at 3, so that the hair wedging in between the bowed portions 3 will lodge between the bowed portions 3 and the point of juncture of the limbs. The numeral 4 designates the outer member so designated because the limbs 5 thereof are arranged upon the outer sides of the limbs 3, that is to say, the limbs 5 are spaced equal distances from the outer surfaces of the limbs 3. Each of the limbs 5 is provided with an outwardly bowed portion 6 arranged in alinement with the inwardly bowed

portions 3 and at this point attention is called to the fact that owing to the relative arrangement of the portions 6 and the bowed portions 3 bulged recesses 7 are formed between the limbs 2 and 5 in which a large amount of hair may lodge. Thus it will be seen that unsymmetric surfaces are provided for gripping the hair. The connecting portion 8 that unites the limbs 5 is coiled around the smooth curved end portion 9 of the central member 1 to form a loop as clearly shown at 10, the curved end portion 9 passes between the sides of the loop and over the portion 8 of the member 4 in such a manner as to hold the central members against twisting around its longitudinal axis that is to say any tendency of the central member to twist in this direction will be prevented by the curved portion 11 at the intersection of the loop with the portion 8, while the curved portion 12 cooperates with the curved portion 11 to prevent twisting of the central member around a transverse axis.

By referring to Fig. 1 it will be readily seen that the curved portions 11 and 12 also effectively hold the central member against upward and downward movement. Thus it will be seen that the central member and the outer member is held against relative bodily movement in any direction, and at the same time does not interfere with the resiliency of the parallel limbs.

From the foregoing description taken in connection with the accompanying drawing it should be apparent that I provide a device which is admirably adapted for the purpose for which it is intended, that the device is simple, durable and efficient of construction, and that the device may be manufactured and sold at a comparatively low cost. Changes in the form, proportion and minor details of construction may be made within the scope of the claims without departing from the spirit or sacrificing any of the advantages of the invention.

What I claim is:

1. A hair pin comprising a U-shaped outer member having a centrally arranged loop in the portion connecting the sides thereof, a U-shaped inner member having a smooth and curved portion connecting the sides thereof, said smooth and curved portion passing between the sides of the loop and over the portion connecting the sides of the first mentioned member, an inwardly bowed

portion between the ends of each of the sides of the inner member, and an outwardly bowed portion in each of the sides of the outer member.

5 2. A hair pin comprising a U-shaped outer member, a U-shaped inner member connected with the outer member and arranged between the sides thereof, said outer member having an outwardly bowed portion on 10 each side thereof, and an inwardly bowed

portion in each side of the inner member alining with the outer bowed portion in a side of the outer portion.

In testimony whereof, I affix my signature.

TORSTEN ALFONSO GYLSDORFF.
